UNITED STATES PATENT OFFICE.

CHARLES A. SNYDER, OF NORFOLK, VIRGINIA.

FASTENING DEVICE.

Application filed May 15, 1926. Serial No. 109,376.

This invention relates to a fastening device adapted to be operatively applied in connection with a sash, movable panel or other analogous movable member to which the device may be applicable.

The primary object of the invention is to hold a window sash, panel or analogous movable member either locked in closed position or in partially open position, and to have 10 the improved fastener of such construction that it may be readily reversed to engage opposite portions of a sash or window frame, panel or other movable member to hold the same against movement.

15 A further object of the invention is to provide a fastener of the class specified, which is simple in construction and economical in manufacture, the improved device, whether used in connection with one or both 20 sides of a sash or window frame, panel or other movable member, being the same in construction, or where two of the improved devices are used, they will be duplicates.

A further object of the invention is to 25 provide a fastening device of the class specified which may also serve to eliminate all vibratory noises or rattling of the window sash, panel or other movable member, and also to effect a tight joint, particularly of a 30 window sash with respect to the inner and outer stops of a window frame, to exclude cold air and thereby render the use of weather strips and like air-excluding means unnecessary.

35 A still further object of the invention is to provide a fastening device of the class specified, which may be readily applied in operative position without requiring any special mechanical knowledge, and moreover, to provide a fastening device which is fool-proof in its construction.

With the foregoing and other objects and advantages in view, the invention consists in the preferred construction and arrangement 45 of the several parts which will be more fully hereinafter described and claimed.

In the drawing:

Fig. 1 is an inside elevation of a portion 50 of a window frame and sash, showing the improved fastening device applied to opposite sides of the sash.

Fig. 2 is an inside elevation of a portion of a window frame and sash, showing one

of the devices in full and dotted lines to illustrate the operation of the same. 55

Fig. 3 is a view similar to Fig. 2, showing one of the improved fastening devices in locking position to prevent raising of the sash.

Fig. 4 is a horizontal section on the line 60 4—4, Fig. 2.

Fig. 5 is a horizontal section on the line 5—5, Fig. 3.

Fig. 6 is a detail perspective view of the 65 preferred form of the improved fastening device.

Fig. 7 is an elevation of a slightly modified form of the fastening device.

The improved fastening device is shown 70 applied to a window sash, a pair of the devices being illustrated as fastened to the side member of the sash in Fig. 1, but it will be understood that the said fastening device will operate with equal efficiency if applied to the inner opposite side portions of 75 the frame and bind against the adjacent side members of the sash. Furthermore, it may at times be desirable to use only one of the improved devices, and it is obvious that the invention will not be in the least modified by 80 either a single or double use of the improved device.

Structurally, the improved device comprises a flat body member 5, of suitable thickness, having the opposite ends 6 and 7 85 struck or bent up at right angles to the body member in the form of flanges. These end flanges are curved in the arcs of circles struck from the centers A and B in the preferred form of the device, and from the 90 centers C and D in the modified form shown by Fig. 7. In the preferred form of the fastening device as shown by Figs. 1 to 6, inclusive, the opposite side edges are of duplicate contour, there being two parallel 95 straight side edge portions intersected at their inner terminals by obtusely-arranged, shorter straight side edge portions 9, which continue outwardly to the curved outer surfaces of the flanges 6 and 7, these curved flanges with the body 5 essentially forming 100 a double cam for reversible operation. The flanges 6 and 7 are equidistant from the center of the body 5, and the general construction of the improved device is such 105 that one standardized form of the same may

be applied to either side of a window frame or in connection with any other movable member to which it may be applicable.

It will be understood that the improved device will be formed of metal and produced by suitable die means, and curved bends are formed between the flanges 6 and 7 and the body to render a die practical in the formation of the improved device.

10 In applying the improved device, it will be impossible to place the same in a wrong position on the side members of the window sash or inner opposite sides of the window frame or panel casing, for the reason that 15 when the device is placed on the casing, it is only necessary to dispose any one of the straight edges 8 or 9 parallel with the edge of the casing or sash or panel casing, as the case may be, with any point touching the edge 20 of the window frame, sash or casing, and if this mode of application is properly followed, the device will be in proper position for operation. When placed on the right side of the inner portion of the window frame or 25 side member of the sash, the device operates as a positive stop to prevent the sash from being lowered, and when the device is placed on the left side of the window frame or sash as shown by Fig. 1, it operates to hold 30 the window against raising movement, and by this means a safety device is provided and also all vibration and rattling noise will be positively eliminated. When the device is applied to both the right and left- 35 hand sides of a window frame or sash in proper operative position, a slight pressure thereon, either downwardly or upwardly as the case may be, will immovably hold the sash or panel in place. When the window sash is 40 closed, as in cold or windy weather, the improved device is operated on both sides to set up a binding action relatively to the window sash and seal the window or tightly hold the same in such manner as to obstruct all 45 ingress of cold air and dust, and by this means the use of weather stripping is obviated. When the window is closed and has the improved device applied to opposite sides thereof as shown in Fig. 1, a sealing 50 of the window sash to obstruct ingress of cold air and dust may be effectively obtained by first pressing outwardly on the sash and then operating the device to lock the sash against movement. On the other hand, when 55 the improved devices are applied to the inner opposing sides of the inner part of the frame or window casing, the pressure of the device on the side portions of the sash will be exerted in an outward direction, 60 either to lock the sash against upward and downward movement, or, when the sash is closed, to seal the same, as above specified. The curved surfaces or opposed cam edges provided by the curved flanges 6 and 7 will

not mar the window sash or the inner opposing sides of the window casing or frame, as the device need only exert a slight binding action between the opposed cam surfaces and the parts of the window sash or frame just referred to to set up a positive locking 70 action.

It is obvious that the improved device may be made in various sizes, but for all practical purposes a standardized size will be adopted 75 and manufactured and have such proportions as to render the device practical for the purpose for which it has been devised.

The improved fastening device is secured in applied position through the medium of one screw 10, which is passed through an 80 opening 11 in the intermediate portion of the body 5, the said screw being of such construction that it firmly holds the device in association with the window sash or inner 85 side of the window frame and at the same time permits a requisite pivotal or swinging movement of the fastening device thereon.

In the modified structure shown by Fig. 7 the features are essentially the same as those described in connection with the preferred form, the difference being in this instance that one extremity 5^a of the body 5 serves as a weight gravitating feature, owing to the eccentricity of the opening 12 corresponding to the opening 11 in the form 90 shown by Fig. 6. Furthermore, the one side edge 13 extends in a straight line almost fully from the flange 6 to the flange 7, there being a short angular straight edge 14 continuing outwardly to the outer surface of the flange 7. The opposite side edge of this modified form is more nearly like the structure shown by Fig. 7 and comprises a straight edge 15 parallel with the edge 13 and an angular straight edge 16, continuing 100 from the edge 15 outwardly to the outer surface of the flange 6.

The operation of this modified structure is essentially the same as that heretofore described in connection with the preferred form and both forms embody the essential features of the invention, namely, the flat body 5, pivotally mounted and having opposite side edges composed of straight lines arranged at an angle to each other 115 and presenting two curved cam flanges for engaging the window sash or adjacent portion of the window frame or corresponding parts of other movable and supporting structures with which the device may be 120 used.

What is claimed as new is:

A reversible fastener for windows, consisting of a flat body formed of one piece of material and having the opposite ends 125 provided with curved flanges projected solely from the outer side of the body and struck from two different centers and whose

outer sides present opposing eccentric cam faces extending reversely over the center of the body, and also having opposite straight parallel side edge guiding portions extending part way the length of the fastener and each terminating at one end with reverse ends of the flanges and their opposite inner terminals intersecting the remaining edge

portions at obtuse angles and which latter edge portions terminate at the ends of said flanges opposite the outer terminals of the said parallel side edge portions. 10

In testimony whereof I have hereunto set my hand.

CHARLES A. SNYDER.
